Non-final Office Action dated Aug. 25, 2022 issued in the Design U.S. Appl. No. 35/512,426.

Primary Examiner — R. Johnson

(57) **CLAIM**

The ornamental design for an electric guitar, as shown and described.

DESCRIPTION

FIG. 1 is a front, top and right side perspective view of an electric guitar showing our new design;

FIG. 2 is a rear, bottom and left side perspective view thereof;

FIG. 3 is a partial enlarged view showing the head part thereof;

FIG. 4 is another partial enlarged view showing the head part thereof;

FIG. 5 is another partial enlarged view showing the head part thereof;

FIG. 6 is another partial enlarged view showing the head part thereof;

FIG. 7 is another partial enlarged view showing the head part thereof;

FIG. 8 is another partial enlarged view showing the head part thereof;

FIG. 9 is another partial enlarged view showing the head part thereof;

FIG. 10 is a front view thereof;

FIG. 11 is a rear view thereof;

FIG. 12 is a top plan view thereof;

FIG. 13 is a bottom plan view thereof; and,

FIG. 14 is a right side view thereof.

The broken lines illustrate portions of the electric guitar that form no part of the claimed design. The dash-dotted lines denote the boundary of the claim and form no part of the claimed design.
